UNITED STATES PATENT OFFICE.

AUGUST P. SPITKO, OF SALT LAKE CITY, UTAH.

NON-SIFTING ENVELOP.

996,532.

Specification of Letters Patent. Patented June 27, 1911.

Application filed April 3, 1911. Serial No. 618,530.

To all whom it may concern:

Be it known that I, AUGUST P. SPITKO, a citizen of the United States, and a resident of Salt Lake City, in the county of Salt 5 Lake, State of Utah, have invented a new and useful Improvement in Non-Sifting Envelops, of which the following is a specification.

My invention is an improvement in the 10 class of envelops designed more especially for carrying merchandise, and the object of the invention is to provide means in connection with the envelop for closing the mouth thereof in such manner as to prevent 15 the escape of comminuted or pulverulent substances at the ends of the flap, where in the ordinary form of envelop there is an opening between the sealing flap and the back of the envelop.

20 In the drawings: Figure 1 is a perspective view of the envelop with the sealing flap closed; Fig. 2 is a similar view of a portion of the envelop with the flap open; Fig. 3 is a front view of a portion of the 25 envelop; Fig. 4 is a section on the line 4—4 of Fig. 3; and Fig. 5 is a sectional view showing the sealing flaps partly folded.

In the embodiment of the invention shown the body 1 of the envelop is formed by folding 30 the side edges 2 of the sheet onto the body 1, the said edges being connected at the longitudinal center of the body, as indicated at 4. The body is extended beyond the side flaps 2 to form a closing flap 5, 35 which is turned over on the flaps 2 and 3 and sealed as shown in Fig. 1. At the opposite end of the envelop the side edges or flaps 2 are cut away to leave a single 40 ply flap 6, and a stiffening strip 7 is superposed on the inner face of the said flap and sealed thereto. The said strip is preferably of thin 45 pasteboard or stiff paper, and at its center the strip is provided with a downwardly 50 projecting tongue 8 having a transverse opening 9. The flap 6 is cut away at its center, as indicated at 10 in Fig. 3, and the flap 6 so formed is secured to the tongue 8.

A fastener is connected with the side flaps 2, the said fastener comprising a T-shaped 55 plate having its body 11 provided with

tongues 12 passed through the flaps and bent over upon themselves to hold the plate in place, and a tongue 13. The envelop is transversely creased at 14 to mark the limits of the flap 6 and is also transversely creased 55 at 15.

In using the improved envelop, after the contents have been inserted in the inclosure, the flap 6 is folded onto the envelop. The crease 15 is so placed that the free edge of 60 the flap 6 registers therewith, and the said crease marks the limits of the double flap formed by the superposing of the flap 6 on that portion 16 of the envelop between the creases 14 and 15. The said double flap is 65 now folded onto the body of the envelop, and the tongue 13 is passed through the opening 9 of the tongue 8 and is then bent downwardly as indicated in Fig. 4. The tongue 13 thus holds the double flap closed. 70 It will be noticed that the envelop has in fact a sealing flap whose inner portion is a double ply, while its outer portion is a single 75 ply, and the flap folds by folding the single ply onto the double ply and then folding the single ply and the double ply onto the envelop.

I claim:

1. An envelop comprising a body having a sealing flap at one end, a stiffening strip 80 arranged transversely of the sealing flap, said strip having a lateral tongue provided with a transverse opening at approximately the center of the strip and extending in the opposite direction from the flap, said flap 85 being cut away at its center to permit the passage of the tongue, the envelop having a transverse crease at the junction of the sealing flap therewith, and a second transverse crease spaced apart from the first 90 crease a distance corresponding approximately to the width of the sealing flap, and forming a double flap between the sealing flap and the body of the envelop, and a flexible metallic tongue on the envelop for 95 engaging the opening of the tongue of the stiffening strip.

2. An envelop comprising a body having a sealing flap, a reinforcing strip arranged transversely of the sealing flap and having a 100

lateral tongue extending in the opposite direction from the flap, the envelop having a transverse crease at the junction of the sealing flap therewith, and having a second transverse crease spaced apart from the first crease a distance corresponding approximately to the width of the sealing flap, and

means on the envelop for holding the tongue of the reinforcing strip.

AUGUST P. SPITKO.
